UNITED STATES PATENT OFFICE.

LEONARD E. WRAY, OF MINNEAPOLIS, MINNESOTA.

TRACK AND TRUCK MECHANISM.

1,335,706.

Specification of Letters Patent. Patented Mar. 30, 1920.

Application filed January 8, 1919. Serial No. 270,169.

To all whom it may concern:

Be it known that I, LEONARD E. WRAY, a citizen of the United States, residing at Minneapolis, in the county of Hennepin and State of Minnesota, have invented certain new and useful Improvements in Track and Truck Mechanism; and I do hereby declare the following to be a full, clear, and exact description of the invention, such as will enable others skilled in the art to which it appertains to make and use the same.

My invention relates to track and truck mechanism intended for general use, and especially adapted for use in transferring truck-equipped distributing spout mechanism from one overhead track to another, of the type disclosed and broadly claimed in my co-pending application, executed of even date herewith, and entitled "Grain spout mechanism."

To the above end, generally stated, the invention consists of the novel devices and combinations of devices hereinafter described and defined in the claims.

In the accompanying drawings, which illustrate the invention, like characters indicate like parts throughout the several views.

Referring to the drawings,

Figure 1 is a view principally in plan with some parts sectioned on the line 1—1 of Fig. 2, and with some parts shown in different positions by means of broken lines;

Fig. 2 is a view principally in side elevation with some parts sectioned on the line 2—2 of Fig. 1;

Fig. 3 is a view principally in plan, with some parts sectioned on the line 3—3 of Fig. 2; and

Fig. 4 is a view in section taken on the line 4—4 of Fig. 2.

The numeral 5 indicates the floor of an overhead storage bin or hopper and the numerals 6 and 7 indicate two parallel laterally spaced overhead main tracks. Each main track 6 and 7 comprises a pair of rails, in the form of a pair of angle bars, the horizontal flanges of which are turned toward each other and the vertical flanges of which are turned downward. The vertical flanges of the rails of each main track 6 and 7 are secured to the lower ends of the prongs of yoke-like brackets 8 suspended from the ceiling of the floor 5 by having their transverse portions bolted thereto. Oblique braces 9 connect the lower ends of the prongs of the brackets 8 to the ceiling of the floor

5, and thereby hold the rails of each main track 6 and 7 against lateral movement and properly spaced.

Extending transversely in front of the 60 left-hand ends of the main tracks 6 and 7 and thereabove, with respect to Fig. 1, is a transverse track 10 also comprising a pair of commercial angle bars arranged in the same manner as the rails of the tracks 6 65 and 7. The rails of this transverse track 10 are also suspended from the ceiling of the floor 5 by brackets 11 of the same form as the brackets 8, except that the prongs thereof are much shorter and, therefore, do not 70 require braces to hold the connected rails against lateral movement.

The numeral 12 indicates a four-wheeled truck mounted to travel on either of the main tracks 6 or 7 and having suspended 75 therefrom a distributing spout 13, said truck and spout being of the type heretofore referred to. This distributing spout mechanism is transferred from one main track to the other by a transfer track section 14 carried by a truck 15 arranged to travel on the transverse track 10. The rails of the track section 14 are of the same form as the rails of the main tracks 6 and 7 and arranged to be brought into longitudinal alignment therewith. The outer ends of these rails are rigidly connected by a stop member 16 also in the form of an angle bar.

The transfer truck 15 comprises a rectangular frame 17 having mounted thereon a pair of axles 18, on the outer ends of which are journaled flanged wheels 19 arranged to run on the rails of the track 10. The track section 14 is suspended from the truck 95 frame 17 by four flat bars 20 held properly spaced at their lower ends by nut-equipped tie rods 21 and long spacing thimbles 22. By reference to Fig. 1, it will be noted that one of the brackets 11 is located at the longitudinal center of each main track 6 and 7 and pivoted to the inner prong of each of said brackets, is a gravity-suspended stop bar 23. These stop bars 23 are arranged to be engaged by an operating lever 12' of the 100 distributing spout mechanism 13, and thereby limit the traveling movement of the truck 12 toward the track 10.

To prevent the transfer truck 15 from being accidentally displaced from the track 11 10 by a lifting movement thereof, there is secured to each side member of its frame 17

22

a pair of L-shaped retaining fingers 24, the horizontal portions of which underlie the rails of said track and, under a lifting movement of the transfer truck, will engage said rails, and thereby prevent the transfer truck from being lifted a distance sufficient to carry the flanges of the wheels 19 above said rails. By reference to Figs. 1 and 2, it will be noted that the horizontal portions of the two retaining fingers 24, on the side of the truck 15 toward the main rails 6 and 7, are made longer than the ones on the other side of said truck, so as to engage and move the stop bars 23 into inoperative positions and out of the path of movement of the truck 12 in traveling from the main tracks onto the transfer track 14 or vice versa. The free ends of the retaining fingers 24, on the side of the truck 15 toward the main tracks 6 and 7, are connected by a tie bar 25. To prevent the truck 12 from running off the track 14, during the transfer thereof from one main track to the other, a guard bar 26 is extended between said main tracks and secured to the brackets 8.

From the above description, it is evident that the truck 12 is limited in its traveling movement on either of the main tracks 6 or 7, toward the track 10, by the gravity-held stop bars 23, to prevent the same from accidentally running off said tracks. To transfer the truck 12, and hence, the spout mechanism carried thereby, from one main track to the other, the truck 15 is moved along the track 10 by a reversely extended cable, or other suitable means, to position the track section 14 in alinement with the main track on which the truck 12 is mounted. In thus positioning the track section 14, the respective stop bar 23 is swung into an inoperative position, as indicated by full lines in Fig. 4, by the engagement of one of the retaining fingers 24 therewith. In this position of the track section 14, the truck 12 is moved thereon by taking hold of the distributing spout and drawing said truck forward. The stop bar 16, of course, limits the traveling movement of the truck 12 onto the track 14 to prevent the same from running off the track.

With the truck 12 on the track 14, the truck 15 is moved along the track 10, until the rails of the track 14 are in alinement with the main track to which the truck 12 is to be transferred. In this positioning of the track 14, the respective stop bar is moved into an operative position, in a manner previously described, to permit the truck 12 to be moved from the track 14 to the respective main track. During the traveling movement of the truck 15 from one main track to the other, the truck 12 is prevented from running off the track 14 by the guide bar 26.

By the use of the truck and track mechanism, just described, it is possible to transfer a distributing spout mechanism from one main track to the other, it being understood that the main tracks are located under discharge spouts leading from overhead storage bins or hoppers and into alinement with any one of said discharge spouts, the spout mechanism may be brought under the traveling movement of the truck 12. It is, of course, understood that any member of the main track may be used and that, in some instances, transverse tracks may be located at both ends of the main track.

What I claim is:—

1. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, a stop at each main track to limit the traveling movement of the main truck toward the transverse track, and means carried by the transfer truck for moving said stops into inoperative positions. 80
2. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, a gravity-positioned stop at each main track to limit the traveling movement of the main truck toward the transverse track, and means carried by the transfer truck for moving said stops into inoperative positions. 95
3. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, and a guard between the main tracks to limit the traveling movement of the main truck on the transfer track section toward said main tracks. 100
4. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, and a guide bar between the main tracks to limit the traveling movement of the main truck on the transfer track section toward said main tracks. 110
5. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, and a guard between the main tracks to limit the traveling movement of the main truck on the transfer track section toward said main tracks. 120
6. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, and a guide bar between the main tracks to limit the traveling movement of the main truck on the transfer track section toward said main tracks. 125
7. The combination with two main tracks and a main truck arranged to travel on either thereof, of a transverse track located above the main tracks, a transfer truck arranged to travel on the transverse track, a transfer track section carried by the transfer truck and arranged to be brought into alinement with either of the main tracks to receive therefrom or deliver thereto the main truck, and a guide bar between the main tracks to limit the traveling movement of the main truck on the transfer track section toward said main tracks. 130

ceive therefrom or deliver thereto the main truck, a gravity-positioned stop at each main track to limit the traveling movement of the main truck toward the transverse track, and 5 retaining fingers carried by the transfer truck to prevent said transfer truck from being lifted from the transverse track, certain of said retaining fingers arranged to en-

gage said stops to move the same into inoperative positions. 10

In testimony whereof I affix my signature in presence of two witnesses.

LEONARD E. WRAY.
